WHIP ROLL COUNTERBALANCE

Fred J. Hagen, Crichton, Ala.

Application April 7, 1939, Serial No. 266,640

2 Claims. (Cl. 139—114)

This invention relates to let-off devices for looms, particularly whip rolls. Specifically, the invention resides in providing a counterbalance for a whip roll.

In developing the invention, it was found that, in order to overcome the constant downward force of the combined weight of the whip roll and whip roll lever, the vibrator rod spring, which normally prevents the whip roll from swinging downwardly, had to be relatively strong. This resulted in excessive strain on the warp yarns, especially during the let-off motions when extra tension was applied to warp yarn so as partially to overcome the vibrator rod spring. The excessive tension on the warp yarns resulted in a narrowing of the fabric, and decrease in the diameter of the warp yarn. It is therefore an object of the invention to decrease the amount of extra tension necessary to compress the vibrator rod spring.

In providing a counterbalance for a whip roll, it is also an object to allow the use of a correspondingly weaker vibrator rod spring, and thus to decrease wear on the harness eyes, jumping of beams when the warp is low, and wear on the machine parts.

It is also intended to provide a counterbalance which may be readily attached either to right or left-hand looms of the standard types, and which may be easily tested and adjusted to suit different warp yarns.

These and other objectives, such as the provision of a counterbalance which is low in original cost, simple in operation, and easy to maintain, will be apparent from the following specification and drawings, in which:

Fig. 1 is a side elevation of the device;

Fig. 2 is a plan view;

Fig. 3 is a vertical section along the line 3—3 of Fig. 2;

Fig. 4 is a vertical section along the line 4—4 of Fig. 1, and

Fig. 5 is a side elevation of the device as installed on a loom.

Referring particularly to Figs. 1 to 4, inclusive, the weight arm 2, which is laterally offset as indicated at 4, is provided with a hub 6 having sets 8 and 10 of teeth. The free end 12 of arm 2 is notched on its upper and lower sides 14 and 16.

Numerical 17 indicates the counterweight, which is adjustably mounted on the weight arm 2 by the means of the pin 18 which extends through the counterweight and through one of the slots 14, as best shown in Figs. 3 and 4, and by the set

screws 22 and 24 which extend through the threaded holes 26 in one side of the counterweight 17.

Because of the offset portion 8 of the weight arm two sets 8 and 10 of teeth on the hub 6, and the sets 14 and 16 of notches on the upper and lower sides of the free end 12 of weight arm 2, the counterbalance may be mounted on either the right or left-hand side of a loom without interfering with adjacent loom parts. When mounted, the counterweight 17 may be adjusted by loosening set screws 22 and 24, and moving the weight along the free end 12 of the arm 2. The pin 18 engages in the notches 14 and holds the weight temporarily until the set screws 22 and 24 are again tightened to engage arm 2 as shown at 28.

Fig. 5 shows the device mounted for operation. In one end of the loom frame 30, the warp beam 20 32 holds warp threads 34 which are passed over the whip roll 36. The whip roll 36 is supported at each end in the usual manner by a pair of arms 38 secured to the shaft 39 by collars 40. As shown in Fig. 5, the shaft is rotatably supported by the loom frame 30. On one end of the shaft 39 is mounted the whip roll lever 42 which is secured tightly against the collars 40 by the nut 41, and has the whip roll lever plug 44 pivoted at its lower end, through which the vibrator rod 46 passes. Preventer spring collar 48 holds one end of the vibrator rod spring 49, the other end being abutted by the member 50. The vibrator rod 46 passes through the member 50, and, as shown at 51, engages the control lever 52 operatively connected to the pallet lever 54 and pallet 56.

The loom may be either of the type in which the whip-roll is positively moved by a let-off motion transmitted upwardly through the vibrator rod and wherein a retroactive control movement is transmitted back through the vibrator rod spring to control the amount of let-off for the warp beam in accordance with the tension of the warp on the whip roll, or it may 45 be of the type in which the whip roll is moved only by the warp.

The hub 6 of the weight arm 2 is attached by removing unit 41, removing the whip roll lever 42, and by inserting the hub over shaft 39 between the lever 42 and collar 40. The teeth 8 bear against the inner face of the upper end of the lever 42 and against the collar 40 and thus prevent relative rotation between the weight arm 2 and the lever 42.

55 When installing the counterbalance on looms

previously in use, the old vibrator rod spring should be replaced by one substantially weaker.

As may be seen in Fig. 5, the counterbalance exerts a force in opposition to the tension of the yarn against the whip roll 36. The weight of the whip roll itself, plus the weight of the supporting parts, and the whip roll lever also exert a force which must be overcome by the spring 49. Since, because of the counterbalance, the tendency of these parts to swing downwardly against the spring 49 is less, the vibrator rod spring need not be of as great initial strength as without the counterbalance. In the weaker spring, the ratio of increase in necessary force to move it between maximum extended and maximum compressed conditions is not as great as with the former, initially stronger spring. In result, there is relatively little difference in the tension of the warp yarn between its normal condition and the let-off periods.

In actual operation, use of the counterbalance has resulted in an increase of approximately 3000 more picks per eight hour day than before with the same loom. The cloth is a full one quarter of an inch wider, and the warp yarn may be made from single creel roving where double creel roving was previously required. By approaching uniform tension at all times, incorrect setting of the let-off motion is compensated for.

While I have described herein some embodiments of my invention, I wish it to be understood that I do not intend to limit myself thereby except within the scope of the appended claims.

I claim:

1. In a whip roll mechanism for a loom having a whip roll supported adjacent the outer ends of a pair of arms connected to a shaft at the inner ends of said arms, said shaft being supported on the frame of said loom, a lever on said shaft, and a spring operatively engaged against the free end of said lever for resiliently holding said whip roll against the warp yarn of said loom and adapted to be compressed during the warp yarn let-off motion of said loom; a counterbalance, said counterbalance being adapted and arranged to

force said whip roll against said warp yarn in supplement to said spring, and comprising a weight arm, means on one end of said weight arm for securing the same to said shaft, a counterweight adjustably secured to the other end of said weight arm, and means for adjusting the position of said counterweight along said weight arm, said weight arm being laterally offset intermediate its length, the first-mentioned means comprising a hub, and teeth on the faces of said hub adjacent the opening thereof, the second-mentioned means comprising a series of teeth along the upper and lower edges of said rod whereby said counterbalance may be used for either right or left-hand looms, said counterweight having an opening through which said weight arm is slidably, and a pin across said opening whereby said counterweight may temporarily be held on said weight arm during adjustment, and set screws threadedly engaged with said counterweight and engageable against said weight arm.

2. In a whip roll mechanism for a loom having a whip roll supported adjacent the outer ends of a pair of arms connected to a shaft at the inner ends of said arms, said shaft being supported on the frame of said loom, a lever on said shaft, and a spring operatively engaged against the free end of said lever for resiliently holding said whip roll against the warp yarn in said loom and adapted to be compressed during the warp yarn let-off motion of said loom; a counterbalance, said counterbalance being adapted and arranged to force said whip roll against said warp yarn in supplement to said spring, and comprising a weight arm, means on one end of said weight arm for securing the same to said shaft, a counterweight adjustably secured to the other end of said weight arm, and means for adjusting the position of said counterweight along said arm, said weight arm being laterally offset intermediate its length, the first-mentioned means comprising a hub, and teeth on the faces of said hub adjacent the opening thereof whereby said counterbalance may be used for either right or left-hand looms.

FRED J. HAGEN.
